DUAL OILING SYSTEM FOR INTERNAL COMBUSTION ENGINES

Charles E. Fisher, Peekskill, N. Y.

Application May 29, 1937, Serial No. 145,405

6 Claims. (Cl. 123—196)

This invention relates to oiling systems for internal combustion engines, and particularly to an improved dual oiling system, the object being to provide a construction wherein oil is supplied temporarily through certain oil distributing members before the first explosion of the combustible mixture.

Another object of the invention is to provide a dual oiling system wherein oil is supplied to the moving parts of the engine before these parts have begun to move and later supply oil to the moving parts through a second supply system.

An additional and further object of the invention is to provide a dual oiling system for combustion engines wherein a special driven pump is utilized for supplying oil temporarily to the parts of the engine and later where a second pump supplies oil to the same parts.

In the accompanying drawings:

Fig. 1 is a view partly in diagram and partly in section disclosing an embodiment of the invention;

Fig. 2 is a longitudinal sectional view through the cylinders of a six cylinder engine showing how oil is supplied thereto;

Fig. 3 is a view principally in section showing how the oiling system supplies oil to the crank shaft of an engine;

Fig. 4 is a longitudinal vertical sectional view through an automatic switch embodying certain features of the invention;

Fig. 5 is a sectional view through Fig. 4 approximately on the line 5—5;

Fig. 6 is a sectional view through Fig. 4 approximately on the line 6—6;

Fig. 7 is an enlarged detail fragmentary sectional view showing one of the check valves used in the oiling system.

Referring to the accompanying drawings by numerals, 1 indicates an internal combustion engine of any desired type provided with any desired form of sump 2. The engine 1 is provided with a number of pistons 3 and a number of cylinders 4. As shown in Fig. 2 there is illustrated six cylinders but the invention could be applied to an engine having more or less cylinders without departing from the spirit of the invention. In the ordinary automobile of today it is customary to turn on the ignition switch and then a little later step on the starter. If the engine is in proper shape it will immediately start and once it starts the ordinary oil pump now in common use will begin to function. However, it will be understood that for the first few movements of the pistons there will be no oil supplied there-

to and this produces an undesired wear. In the present invention oil is supplied to the pistons before they start to move and the supply is continued after they start to move.

In carrying out this idea there is provided a pump 5 which may be an ordinary gear pump or any other suitable kind for forcing oil through the pipe 6 as indicated by the arrow 7. The pump 5 is arranged in the hood 8 supplied with the wire mesh 9. The hood 8 is secured to the tubular casing 10 which is bolted or otherwise rigidly secured to the lower part of the engine 1 as shown in Fig. 1. A drive shaft 11 is connected with the pump 5 and with an electric motor 12 whereby whenever the motor is functioning pump 5 will be functioning. The motor 12 is supplied with current from the battery 13 which is the usual battery on an automobile. This battery has one side grounded at 14 in the usual way and the other side connected to one side of the ignition switch 15. The other side of the ignition switch, namely contact 16, is connected to an automatically operated switch structure 17 by a conductor 18. Current passing through the switch structure 17 will also pass through the conductor 19 to motor 12 which is grounded at 20. It will thus be seen that whenever the switch structure 17 is closed and the ignition switch is closed the motor 12 will be supplied with current and will cause pump 5 to function. It will be understood that the wires 21 and 22 form part of the usual ignition circuit of the engine so that when the switch arm 15' is first closed current will be supplied from battery 13 to the ignition circuit and also to motor 12, which motor will immediately begin to function and cause oil to pass to the cylinders. Ordinarily in starting an automobile there is a few seconds delay between the time that the ignition switch is closed and the time that the starter turns over the engine. During this time whether it is long or short pump 5 will be functioning to force oil to the cylinders of the engine so that the pistons will be supplied with oil before they begin to move for the first time.

As the pump 5 functions oil will pass from pipe 6 to the various pipes 61 leading to the cylinders of the automobile. In addition to the oil passing as just described, some of the oil will pass through the check valve 24 which is shown in detail in Fig. 7. From this figure it will be seen that oil passing upwardly through pipe 61 will unseat the ball 25 and pass on through the pipe 26 while oil from pipe 26 can not move back through the valve 24. From pipe 26 some of the oil passes

upwardly through pipe 27 to produce a desired pressure in the oil gauge 28. Also oil will pass from pipe 26 through pipe 29 to the expanding bellows 30 as shown particularly in Fig. 4. Bellows 30 is supported by a suitable housing 31 and carries a top plate 32 having arms 33 extending into slots 34 of the housing whereby it is guided in its upward and downward movement. As the oil moves into the bellows 30 it attempts to raise the same but there is not sufficient force to raise the plate 32 sufficiently high to actuate the switch arm 35. Spring 36 acts on the plate 32 and on a plate 37. Spring 36 continually tends to force the plate 32 downwardly and also acts to force the same downwardly when there is no counter-pressure in the bellows 30.

By reason of the structure just described motor 12 will force oil to the cylinders of the automobile and also create a pressure in bellows 30 which is not sufficient to raise the parts so as to throw the switch arm 35. This is caused by the way the relief valve 38 in pipe 6 is set. This valve is set to accomplish the result just described and when the pressure from pump 5 raises the plate 32 and associated parts a certain distance, the resistance of spring 36 will be such that it can not move further but the oil will pass out through the relief valve 38 back into the sump 2. This action will continue as long as the switch arm 15' is closed and the engine is not functioning. As soon as the engine begins to function the usual pump 39 of the engine begins to function. This pump is preferably more powerful than pump 5 so that this pump will force oil upwardly through pipe 40 past the check valve 41, which check valve is similar to the valve shown in Fig. 7. Oil passing valve 41 will pass through pipe 42 into pipe 26 and also into pipes 27 and 29. The oil passing from pipe 42 into pipe 26 will close check valve 24 while the low pressure pump 5 is still operating. However, oil leaving pipe 26 at B will pass down through pipe 23 to the bearing at C. This action continues while either pump is operating. Oil passing upwardly through pipe 29 will create sufficient pressure in the bellows 30 to rather quickly raise the plate 32 and the stem 43 carried thereby so that the flat spring 44 will quickly throw the switch base 45 upwardly at one end and downwardly at the other end. The switch arm 35 is rigidly secured by a screw 46 or otherwise to the base 45 and consequently when this base is thrown upwardly or rotated on the pin 47, arm 35 will move out of the socket 48 which forms part of the contact member 49.

It will be understood that wire 18 is connected with contact 49 as shown in Fig. 5 and wire 19 is connected with the pin 47. It will therefore be seen that when the bellows 30 is moved upwardly and the switch arm 35 is swung downwardly the circuit of motor 12 will be opened but the ignition circuit will remain closed. In order to cause a quick action both upwardly and downwardly as shown in Fig. 4 for the base 45 a spring 50 is connected with pin 51 and with a stationary post 52. This spring is preferably under tension at all times to give the action just described. The spring 44 is sufficiently stiff to swing the base 45 upwardly or downwardly as shown in Fig. 4 as the plate 32 moves upwardly and downwardly.

During the normal functioning of the engine whether it is operating at a high speed or low speed, pump 39 will supply sufficient pressure to bellows 30 to maintain the switch structure 17 open and consequently the motor 12 is deprived

of current. If for any reason the engine should stall and the parts stop moving, the pressure in bellows 30 would be relieved and the switch structure 17 would function to move the parts to the position shown in Fig. 4, whereupon motor 12 would begin to function. This motor would be immediately cut out upon starting of the engine as above described or if the switch arm 35 was moved to an open position. It will therefore be seen that oil is supplied to the moving parts before and during the operation of the engine.

I claim:

1. A dual oiling system for an internal combustion engine including a pump for forcing oil through said oiling system, an electric motor for actuating said pump, means for conducting current to said electric motor upon the closing of the ignition circuit of the engine, and means including a pump actuated by said engine for continuing the movement of the oil through the same oiling system after the engine starts and substantially at the same time opening the circuit of said electric motor.

2. An oiling system for an internal combustion engine comprising suitable supply pipes extending to the surfaces to be oiled, an electric motor actuated pump for supplying oil to said pipes, a second pump actuated from the moving parts of the engine for supplying oil to said pipes, an electric circuit for said electric motor, said electric circuit including the ignition switch of the engine and a pressure controlled automatic switch, and means actuated by pressure from the second mentioned pump for opening said automatic switch.

3. An oiling system for an internal combustion engine provided with the usual oil distributing pipes and oil pump comprising a special oil pump, an electric motor for forcing oil through said pipes, a relief valve for said special pump, an electric circuit for said motor including the battery associated with the engine and also the ignition switch, an automatic pressure throw-out switch inserted in said circuit, means including a bellows for opening said throw-out switch, means for directing oil from the pump of the engine for causing said bellows to function, and two check valves for preventing oil passing from either pump to the other.

4. In an oiling system for internal combustion engines, a pair of pumps for supplying oil to said system, one of said pumps being driven from the moving parts of the engine, an electric motor for driving the other pump, check valves for preventing oil from either pump passing back to the other, a circuit for said electric motor including the ignition switch of the engine whereby current is supplied to said motor when the ignition switch of the engine is closed, a pressure throw-out switch arranged in said circuit, said throw-out switch including a stationary contact, a swingable switch arm, a reciprocating member, means coacting with the reciprocating member for swinging said switch arm into and out of engagement with said stationary contact, a spring for moving said means in one direction, and a bellows operated by pressure from the regular pump of the engine for moving the switch arm to an open position.

5. In an oiling system for an internal combustion engine including an electrically actuated pump, a standard pump operated by the mechanism of the engine, a circuit for the electrically actuated pump, said circuit including the ignition switch of the engine and a pressure actuated

throw-out switch, said throw-out switch including a stationary contact, a switch arm adapted to be moved into and out of engagement with the stationary contact, a reciprocating structure for swinging said arm, a spring for moving said reciprocating structure in one direction, a bellows for moving said reciprocating structure in the opposite direction, and an oil pipe extending from the second mentioned pump to the bellows whereby when the second mentioned pump is functioning said bellows will be distended for moving said switch arm to an open position.

6. An oiling system for internal combustion engines including an electric motor, an oil pump actuated by the electric motor, a second pump connected with the moving parts of the engine so as to be actuated thereby, a circuit for said motor including the ignition switch of the engine and a pressure throw-out switch, and means actuated by oil from said second pump for opening said throw-out switch after the engine starts to function. 5
